GASEOUS-DISCHARGE MAKE-ALIVE DEVICE

John L. Boyer and Joseph Slepian, Pittsburgh, Pa., assignors to Westinghouse Electric Corporation, East Pittsburgh, Pa., a corporation of Pennsylvania

Application March 31, 1951, Serial No. 218,584

20 Claims. (Cl. 313—170)

1

Our invention relates to single-anode, pool-type vapor-arc rectifiers or asymmetrically conducting devices, having a new make-alive means and method, for initiating the cathode-spark of an arc at the beginning of each conducting period of the device. Our invention is an improvement over, or an alternative for, the broad invention which is described and claimed in the Boyer application, Serial No. 206,434, filed January 17, 1951, for a vapor-arc device, which was characterized by having a spaced starting-anode, as distinguished from a high-resistance or semiconductive ignitor-body which dips down into the cathode-pool as described and claimed in an earlier Slepian and Ludwig ignitron Patent 2,069,283, granted February 2, 1937.

The vapor-arc device covered by the above-mentioned Boyer application was characterized by a relatively large spacing between the starting-anode and the cathode, as compared with the spacing between the main anode and the cathode, in combination with suitable shielding-means for causing the breakdown-discharge from the starting anode to always terminate on the cathode, rather than on the main anode. In this Boyer device, the large starting-anode spacing or distance d , from the cathode, was the means for reducing the voltage necessary to break down the gap between the starting-anode and the cathode, because it produced a relatively large value of the pressure-distance product pd , since the same vapor-pressure p is applicable, of course, to both the main anode and the starting-anode.

In accordance with our present invention, we dispense with the necessity for having a relatively large starting-anode spacing; by using, instead, a magnetic field which causes the electrons to move with an oscillatory or spiral motion in reaching the starting-anode, thereby increasing the distances through which the electrons move, and thus greatly increasing the probability of collisions, so that the breakdown-voltage of the starting-anode is relatively low, notwithstanding the fact that it may have a relatively small physical spacing from the cathode.

Our invention is desirable, as a substitute for the high-resistance dip-in type of igniter make-alive, in asymmetrically conducting vapor-arc devices in which the cathode comprises a pool of mercury as described in the above-mentioned Slepian-Ludwig patent. However, a probably more important field of application of our present invention is in connection with single-anode pool-type alkali-metal tubes, wherein the discharge-metal is a metal chosen from the group comprising

the three heavier stable light metals of the alkali-metal group, comprising cesium, rubidium and potassium, as more particularly described and claimed in an application of Boyer and Colaiaco, Serial No. 144,354, filed February 15, 1950. In single-anode pool-type alkali-metal rectifiers, some sort of spaced starting-anode is a necessity, because the previously known semiconducting ignitor-materials have not been usable in contact with the extremely chemically active alkali-metals, cesium, rubidium or potassium, which wet almost anything, and soak up into the pores of the igniter.

Our invention can be used with any one of several discharge-metals for forming the vaporizable reconstructing cathode-material, including any metals capable of forming a liquid pool at a reasonable temperature, and also having the necessary low-arc-drop characteristics. The best known discharge-metals of this type include mercury, cadmium, cesium, rubidium and potassium. Our novel excitation-method is particularly significant in connection with alkali-metal tubes, of a type using a pool-type vaporizable reconstructing cathode-material consisting of either cesium, rubidium or potassium. By a pool-type tube or valve, we mean any tube or valve in which the active cathode-material is both vaporizable and reconstructing. It may be either an open pool, or a sponge-held pool in which a porous substantially non-vaporizable material holds at least the active portion of the vaporizable reconstructing cathode-material, or an open-pool having therein many vertically disposed baffles which are spaced by distances larger than the capillary dimensions which distinguish a sponge-like material.

Several illustrative forms of embodiment of our present invention are shown in the accompanying drawings, wherein:

Fig. 1 and 2 are somewhat diagrammatic and much simplified vertical elevations, not to scale, illustrative of two different forms of embodiment of our invention; and

Fig. 3 is a schematic diagram of illustrative circuits and connections which are usable with any of the forms of embodiment of our invention and, which are shown, in Fig. 3, in connection with a simplified diagrammatic illustration, not to scale, of a third form of embodiment of our tube.

As shown in Fig. 1, our novel rectifier-tube is an asymmetrically conducting vapor-arc device which comprises an evacuated container 6 having two, and only two, main electrodes 7 and 8 thereof. The main metallic portions of the evacuated

container 6 (as distinguished from the insulator or insulator-seal portions thereof, which will subsequently be described), are preferably made of iron or steel, although other metals could be used. Each tube thus constitutes a single-phase rectifier, for interchanging power between two circuits, such as an alternating-current circuit, and a direct-current circuit. In Fig. 3, the alternating-current circuit is illustrated as a three-phase supply-circuit 10, and the direct-current circuit is indicated as a direct-current load-circuit 11; and a separate rectifier-tube 6 is used for each of the three phases of the supply-circuit 10.

Each tube 6 is also provided with an auxiliary starting-anode 12, for the purpose of exciting the tube at the beginning of each conducting-period of the two main electrodes 7 and 8. In accordance with my present invention, the cathode 8 is a pool type of cathode, and hence it is necessarily or preferably disposed below the main anode 7, so that it is the lower one of the two main electrodes 7 and 8. The cathode-pool 13 consists of a vaporizable reconstructing cathode-material, which is preferably selected from the group comprising mercury, cadmium, cesium, rubidium and potassium, and which still more preferably is selected from the group comprising cesium, rubidium and potassium, with particular emphasis on cesium as the vaporizable reconstructing cathode-material.

As will be described in connection with Fig. 2, this cathode-pool 13 may be an open pool, but it is preferable, for a number of reasons, that the pool-material, or vaporizable reconstructing discharge-metal, should be held by a porous substantially non-vaporizable material in the form of a sponge or partition-filled structure with spaces of capillary dimensions between the partitions, as indicated at 14 in Fig. 1. This porous material can be one of the high-temperature conductors, such as molybdenum, tungsten, tantalum, ruthenium or carbon. The discharge-metal 13 saturates the cathode-sponge 14, but if there is a small amount more than necessary, it can collect in the space around the rim of the sponge, or in any other suitable space which might be provided.

It is necessary that the discharge-metal 13 should wet the sponge, so that it will flow readily through the capillary spaces thereof. When mercury is used as the vaporizable cathode, the sponge has to have a preliminary treatment with hydrogen at a high temperature, in order that the mercury may wet the sponge-material readily, but when either cesium, rubidium or potassium is used, it is not necessary to preliminarily treat the sponge since these alkali-metals wet other materials so easily.

The main anode 7 and the auxiliary starting-anode 12 have to be separately insulatingly supported so that both are spaced and insulated from each other, and from the cathode 8. In the form of embodiment of my invention shown in Fig. 1, both of these insulating supporting structures are a part of the evacuated container 6. Thus, the main anode 7 is separated from the main cathode 8 by a glass-metal seal 18, 19, 20, in which thin metal spinnings 18 and 20 are sealed between a tubular glass member 19 and the main anode and cathode structures 7 and 8, respectively. When a chemically active discharge-metal is used, such as cesium, rubidium or potassium, the metal spinnings 18 and 20 of the seal should be plated internally with either titanium or zirconium, or perhaps with beryllium, or even

chromium, as described in the aforesaid application of Boyer and Colaiaco, in order to prevent the reduction of the oxides of the glass by the chemically active discharge-metal when the tube is up to the correct operating-temperature.

Our starting-electrode 12 is disposed in the space between the main anode 7 and the cathode 13, and is illustrated as being supported by a stiff rod 22 which extends through an inclined tubular projection 23 which extends out, on one side of the device, from the side walls of the cathode-member 8, immediately above the cathode-pool 13. This side-projection 23 is provided with a starting-anode glass-metal seal-portion 25, 26, 27, which extends out from the tubular metal projection 23. The thin metal spinnings 25 and 27 are sealed between the tubular glass member 26 and the starting-anode supporting-rod 22 and the tubular metal projection 23, respectively, in a manner already described in connection with the main glass-metal seal 18, 19, 20.

In the form of our invention which is shown in Fig. 1, the upper main electrode or anode 7 has a hollow or tubular reentrant-portion 31 which extends down into the device from the top of the container. The active portion of the main anode 7 is a flat metal piece 7', which is secured to the bottom of the reentrant portion 31. The main anode 7 is cooled by means of a cylindrical baffle 34, which extends down into the reentrant anode-structure, so that a cooling-fluid (either gas or liquid) may enter over the top of the rectifier-tank 6, as shown by the arrow 35, being then directed downwardly, by the anode-baffle cylinder 34, so as to play on the active main-anode portion 7' at the bottom of the anode, after which the cooling-fluid is discharged upwardly out of the rectifier-tank. To facilitate the heat-exchange, the upper portion of the active anode-portion or main anode-plate 7' may be in good thermal contact with a heavy copper heat-exchange member 36, which is provided with fins 37 for facilitating the heat-transfer from the cooling-fluid to the copper plate 36.

As explained in the previously mentioned Boyer application, the cathode-pool 13 should preferably be the coolest portion of the device, so that its temperature will be the condensation-temperature of the vaporizable reconstructing cathode-material, thus determining the vapor-pressure p of the device. As set forth in said Boyer application, the cathode-cooling may be effected by means of a heavy copper plate 38 which is secured in good thermal contact to the bottom of the cathode-header 8' which lies underneath the cathode-pool 13. The bottom of the heavy copper plate 38 is in turn in good thermal contact with a removable copper plate 39 which is provided with cooling-fins 39' for keeping the cathode at the desired operating temperature according to the desired vapor-pressure p of the device.

In accordance with our present invention, we use some sort of magnet-means for establishing a magnetic field in the vicinity of the starting-anode 12, so as to facilitate a breakdown between said starting-anode and the cathode-pool 13, in order thereby to initiate an arc between the main anode 7 and the cathode 13 at the beginning of each conducting period of the device. Various structures and arrangements may be used for providing a make-alive means which is composed of the combination of a starting-anode and some sort of magnet-means. The general principle 75 is that the starting-anode 12 shall be so disposed

that at least a portion of the magnetic field 40 of the magnet-means shall extend at an angle with respect to at least a portion of the electrostatic field 41 between the starting-anode 12 and the cathode 13.

Thus, in the form of embodiment of our invention which is shown in Fig. 1, the magnet-means comprises two vertically disposed permanent bar-shaped magnets 43 and 44. The top magnet 43 is disposed centrally within the reentrant anode 7, with one of its poles, such as the south pole S (the polarity being immaterial), disposed on top of the flat active anode-portion 1' of the main anode 7. The lower magnet 44 is disposed underneath the cathode-header 8', so that it presents, to the bottom of the cathode header 8', a pole (such as a north pole N) having a polarity opposite to the pole of the upper magnet 43 which is presented to the top of the active anode-portion 1' of the main anode 7.

Although the starting-anode 12 may have any shape and disposition that will produce an electrostatic field 41 which has a substantial component which is cut, at an angle, by some part of the magnetic field 40, we prefer to use some sort of loop or ring-shaped arrangement for the active end or tip of the starting-anode 12. The inactive portion of the starting-anode supporting-rod 22, which extends in the space between the main anode 7 and the cathode-pool 13, is preferably shielded by a metal shield 46 which may be at substantially the cathode-potential, so as to prevent breakdown from this rod 22 to the cathode 13, as shown in each of the figures of our drawing.

In the form of embodiment of our invention which is shown in Fig. 1, the starting-anode 12 has an active portion in the form of a horizontally disposed ring or loop-shaped member which consists essentially of two spaced electrically connected portions 12' and 12'', which are joined at one or both of their ends by means of an end portion 12'''. This loop is so disposed that a substantial portion of the magnetic field 40 of the magnetic-means 43-44 flows through between the two spaced starting-anode portions 12' and 12''.

When it is desired to fire the tube, the starting-anode 12 is made positive with respect to the cathode-pool 12 by about 3,000 volts, or any other suitable make-alive voltage or voltage-impulse. The free electrons in the electric or electrostatic field 41 will be accelerated, by said field, toward the positive ring, along the lines of the electrostatic field, but because of the vertical magnetic field 40, the electrons are forced to move mostly at an angle to the electric field. In doing this, the electrons move in a spiral or oscillatory path, going from side to side, and back again, before reaching the ring, so that the effective length of the electron-path is made large, in a small space, thus greatly increasing the probability of collisions, whereby more electrons and positive ions are formed. The positive ions move to the anode 7' and to the cathode 13, but most of the positive ions move to the cathode, because the anode is positive with respect to the cathode.

The resulting positive-ion bombardment, on both the anode and the cathode, in this abnormal magnetically induced glow-condition, causes a cathode-spot to quickly form on the cathode. Occasionally, a cathode-spot may momentarily form on the anode 7', but it cannot be developed, and instantly goes out, because the anode is positive with respect to the cathode. In the case of the cathode-pool 13, however, once a cathode-

spot has formed thereon, the main anode 7 can pick up an arc therefrom, and instantly begin to carry the main load of the device.

It is desirable to provide some means for preventing the formation of a cathode-spot on the main anode 7 during the non-conducting periods of the device. Various means to this end may be adopted. In Fig. 1, it will be noted that the vertical magnetic field of 40 is substantially in alignment with the vertical electrostatic field (not indicated) between the main anode-portion 7' and the cathode-pool 13, so that the magnetic flux 40 does not materially cut the electrostatic lines of force between the main anode and the cathode, and hence does not deflect the electrons moving in this field, and does not substantially reduce the normal breakdown-voltage in the gap between the main anode and the cathode, so that this main-anode breakdown-voltage is considerably higher than the inverse or negative voltage which is applied to the main anode 7 during the non-conducting periods of the device.

In all of the forms of embodiment of our invention, because of or use of a magnetic field, it is usually desirable to use non-magnetic material, such as stainless steel, for at least those portions of the container which are in the vicinity of the magnetic field 40. Thus, the active plate-portion 7' of the main anode and the cathode-header 8' may be made of stainless steel, or even the whole main anode 7 and the whole cathode 8 may be made of stainless steel.

Fig. 2 shows a modified form of our invention, using a sort of anode and grid-structure which is more similar to the type which has become standard in ignitrons of the kind covered by the Slepian-Ludwig patent. In this form of our invention, the cathode-portion 8 of the container 6 is shown as a metal tank 48 having a metal top 49 which is provided with a central hole or perforation 50. The main anode is shown as a solid anode-member 52, having an upwardly extending stem 53 which is supported from the upper, cap-shaped spinning 18' of a tubular upwardly extending glass-metal seal-portion 18'-19'-20' which extends up from around the hole 50 in the top 49 of the tank 48.

In Fig. 2, the main anode 52 is surrounded by a spaced conducting grid-member 55, which is shown as being suspended from a metal ring 55' which is secured to the bottom of the top 49 of the tank 48, so that the grid 55 is at substantially the tank-potential, which is the cathode-potential of the device. The active reconstructing cathode-material, in Fig. 2, is shown as an open-type pool 13'.

In Fig. 2, the magnet-means is shown as a permanent magnet 56 which lies horizontally, immersed in the cathode-pool 13', with its north and south poles N and S pointing upwardly and lying just below the surface of the pool. The starting-anode ring 12a is now disposed in a vertical plane, so that the magnetic flux, from the magnet 56, will flow horizontally through the ring, so as to increase the length of the electron-paths in a manner already described.

By reason of the use of the anode-shielding grid 55, it is feasible to use a larger spacing between the main anode 52 and the cathode-pool 13', in Fig. 2, as compared to the spacing in Fig. 1, and hence there is ample room for the vertical disposition of the starting-anode ring 12a. According to this construction, a cathode spot can be formed on the pool-surface above either pole 75 of the magnet 56.

If desired, in Fig. 2, suitable shielding-means may be provided, for preventing the formation of cathode-spots outside of the main or central cathode-surface. This shielding-means may take the form of an insulating ring 57, immersed in the cathode-pool 13' and surrounding the magnet 56. The insulating ring 57 may extend above the top surface of the pool and may be connected to the bore of an insulating washer 58 which overlies the top edges of the bore for preventing a cathode-spot from forming in this region.

In the form of our invention which is shown in Fig. 2, it will be noted that the starting-anode ring 12a lies in a plane which is substantially in alignment with the electrostatic field between the main anode 52 and the cathode 13', so that the magnetic field extends at an angle to the electrostatic field of the main anode 52, as well as being at an angle to the electrostatic field of the starting-anode 12a. This circumstance might tend to produce cathode-spots on the main anode 52 during the non-conducting periods of the device, when the main anode is negative with respect to the cathode 13', if it were not for the shielding effect of the grid 55, which is substantially at the cathode potential, and which thus kills the electrostatic field between the main anode 52 and the cathode-pool 13. With the cathode-potential grid 55 in place, the electrostatic field surrounding the main anode 52 extends only to the grid 55, and does not extend on, through the magnetic field, to the cathode-pool 13'. In this way, backfiring is prevented, during the nonconducting periods of the device.

In Fig. 3, we show another means whereby backfiring may be prevented during nonconducting periods of the device, without having to rely, for this purpose, upon an anode-shielding grid such as is shown at 55 in Fig. 2. In Fig. 3, we show the magnet-means as a U-shaped electromagnet 61, which is provided with an energizing-coil 62 so that the magnet can be deenergized during the nonconducting periods of the device, so that its magnetic field will not be present to reduce the breakdown-voltage of the main anode during the times when that breakdown-voltage is needed in order to enable the tube to remain nonconducting during the nonconducting periods when a negative voltage is applied to the main anode. The tube-construction which is shown in Fig. 3 is similar to that which is shown in Fig. 1, except that the two permanent magnets 43 and 44 of Fig. 1 are removed, the starting-anode loop 12 is turned into a vertical plane as shown at 12a in Fig. 3 and as described in Fig. 2, and the electromagnet 61 is placed underneath the cathode-header 8', so that it produces magnetic flux which threads horizontally through the vertically disposed starting-anode loop 12a.

Fig. 3 also shows a form of electrical connection which is presented for merely illustrative purposes, as there are many forms of electrical connections which could be used with our invention. It will be understood, of course, that the electrical connections (minus the electromagnet-connections) which are shown in Fig. 3 could be used with either of the other forms of embodiment of our invention, which are shown in Figs. 1 and 2.

Fig. 3 shows the essential parts of a complete three-phase system, using three tubes 6 of the type which we have just described. Current from the three-phase supply-line 10 is fed to the three main anodes 7 through a main transformer 63, in any of several well-known ways. The three

cathodes 8 are connected to a common cathode-circuit 64, which constitutes the positive terminal of the direct-current load 11. The negative terminal of the direct-current load is the secondary neutral of the main transformer 63.

An exemplary excitation or firing-system for the starting-anodes 12 or 12a consists essentially of a firing transformer 66, which is energized from the polyphase supply-line 10, and charges three firing-capacitors 67 through charging-rectifiers 68. The respective firing-capacitors 67 are discharged, at suitable times, to the respective starting-anodes 12 or 12a, by means of grid-controlled tubes 69 which are provided with suitable phase-controlling means 70 for controlling the portion of the cycle in which each of the tubes 6 is started or fired, thus controlling the output-voltage of the rectifier-assembly. This is only one of several suitable firing-circuits which could be used for the single-anode rectifiers 6.

Usually, it is desirable to provide, also, some sort of sustaining keep-alive means for keeping the main rectifier-tubes 6 from going out under very light load-conditions in the direct-current load-circuit 11. A suitable means for this purpose could include a line-energized low-voltage transformer 73, the secondary terminals of which are connected to the three starting-anodes 12 or 12a through suitable isolating-rectifiers 74.

Where electromagnets 61 are used, as shown in Fig. 3, the three energizing-windings 62 may be energized, preferably only during half-cycle periods, or even shorter portions of each cycle, by means of a suitable step-down transformer 76, having primary windings which are energized from the supply-line 10, and having secondary windings which are connected to the respective electromagnet-windings 62 of the three tubes 6 through rectifiers 78. Preferably, as shown, the secondary windings of the magnet-supplying transformer 76 are phased slightly in advance of the corresponding main anodes 7 of the respective tubes, so as to give the magnetic flux of the electromagnets 61 time to build up in time for the beginning of the half-cycle of positive voltage which is applied to the respective main anodes.

While we have described our invention in several much simplified and diagrammatically indicated exemplary forms of embodiment, with a single exemplary form of embodiment of a suitable electric-circuit connection therefore, we wish it to be understood that our invention is not limited to these details. We desire, therefore, that the appended claims shall be accorded the broadest construction consistent with their language.

We claim as our invention:

1. An asymmetrically conducting vapor-arc device comprising an evacuated container having two, and only two, main electrodes therein and also having an auxiliary starting-anode therein, the operating portion of one of said main electrodes including a vaporizable reconstructing cathode-material, the operating portion of the other one of said main electrodes including an active face-portion comprising the active main anode of the device, means for separately insulatingly supporting said main anode and said starting-anode so that both are spaced and insulated from each other and from the cathode, and make-alive means including a magnet-means for establishing a magnetic field which is

substantially out of alignment with at least a substantial portion of the electrostatic field between said starting-anode and said cathode so as to facilitate a breakdown between said starting-anode and said cathode in order thereby to initiate an arc between the main anode and the cathode.

2. The invention as defined in claim 1, characterized by a disposition of the starting-anode such that at least a substantial portion of the electrostatic field between the starting-anode and the cathode is substantially out of alignment with the electrostatic field between the main anode and the cathode, and a disposition of the magnet-means such that its magnetic field is substantially in alignment with the electrostatic field between the main anode and the cathode.

3. The invention as defined in claim 1, characterized by a disposition of the starting-anode such that at least a substantial portion of the electrostatic field between the starting-anode and the cathode is substantially in alignment with the electrostatic field between the main anode and the cathode, and a disposition of the magnet-means such that its magnetic field is substantially out of alignment with both of said electrostatic fields, in combination with means for preventing a formation of a cathode-spot on the main anode during the non-conducting periods of the device.

4. The invention, as defined in claim 1, characterized by a disposition of the starting-anode such that at least a substantial portion of the electrostatic field between the starting-anode and the cathode is substantially in alignment with the electrostatic field between the main anode and the cathode, and a disposition of the magnet-means such that its magnetic field is substantially out of alignment with both of said electrostatic fields, in combination with an anode-shield for at times preventing a formation of a cathode-spot on the main anode during the non-conducting periods of the device.

5. The invention as defined in claim 1, characterized by said magnet-means being an electromagnet.

6. The invention as defined in claim 5, in combination with means for energizing said electromagnet in readiness for a make-alive operation and deenergizing said electromagnet during times when a cathode-spot might otherwise be produced on the main anode during the non-conducting periods of the device.

7. The invention as defined in claim 5, characterized by a disposition of the starting-anode such that at least a substantial portion of the electrostatic field between the starting-anode and the cathode is substantially in alignment with the electrostatic field between the main anode and the cathode, and a disposition of the magnet-means such that its magnetic field is substantially out of alignment with both of said electrostatic fields.

8. The invention as defined in claim 1, characterized by the operating portion of said starting-anode comprising two spaced electrically connected portions, and a disposition of said magnet-means such that a substantial portion of its magnetic field flows through between said spaced starting-anode portions.

9. The invention as defined in claim 8, characterized by said spaced starting-anode portions lying in a plane which is substantially out of alignment with the electrostatic field between the main anode and the cathode, and a disposition of

the magnet-means such that its magnetic field is substantially in alignment with the electrostatic field between the main anode and the cathode.

5 10. The invention as defined in claim 8, characterized by said spaced starting-anode portions lying in a plane which is substantially parallel to the active cathode surface.

10 11. The invention as defined in claim 8, characterized by said spaced starting-anode portions lying in a plane which is substantially in alignment with the electrostatic field between the main anode and the cathode, and a disposition of the magnet-means such that its magnetic field is substantially out of alignment with both of said electrostatic fields, in combination with means for preventing a formation of a cathode-spot on the main anode during the non-conducting periods of the device.

15 12. The invention as defined in claim 8, characterized by said spaced starting-anode portions lying in a plane which is substantially in alignment with the electrostatic field between the main anode and the cathode, and a disposition of the magnet-means such that its magnetic field is substantially out of alignment with both of said electrostatic fields, in combination with an anode-shield for at times preventing a formation of a cathode-spot on the main anode during the non-conducting periods of the device.

20 13. The invention as defined in claim 8, characterized by said spaced starting-anode portions lying in a plane which is substantially normal to the active cathode surface, in combination with means for preventing a formation of a cathode-spot on the main anodes during the non-conducting periods of the device.

25 14. The invention as defined in claim 8, characterized by said spaced starting-anode portions lying in a plane which is substantially normal to the active cathode surface, in combination with an anode-shield for at times preventing a formation of a cathode-spot on the main anode during the non-conducting periods of the device.

30 15. The invention as defined in claim 8, characterized by said spaced starting-anode portions lying in a plane which is substantially normal to the active cathode surface, and further characterized by said magnet-means being an electromagnet disposed outside of the evacuated container and having two spaced pole-pieces disposed so that north and south magnetic poles are formed at spaced places on the active cathode surface.

35 16. An asymmetrically conducting vapor-arc device comprising an evacuated container having two, and only two, main electrodes therein and also having an auxiliary starting-anode therein, the operating portion of one of said main electrodes including a vaporizable reconstructing cathode-material, the operating portion of the other one of said main electrodes including an active face-portion comprising the active main anode of the device, means for separately insulatingly supporting said main anode and said starting-anode so that both are spaced and insulated from each other and from the cathode, the operating portion of said starting-anode

40 60 65 70 75 being substantially ring-shaped, and a magnet-means for establishing a magnetic field extending substantially in an axial direction through said ring-shaped operating portion of the starting-anode so as to facilitate a breakdown between said ring-shaped portion and the cathode in

11

order thereby to initiate an arc between the main anode and the cathode.

17. The invention as defined in claim 16, characterized by said ring-shaped starting-anode portion lying in a plane which is substantially parallel to the active cathode surface.

18. The invention as defined in claim 16, characterized by said ring-shaped starting-anode portion lying in a plane which is substantially normal to the active cathode surface, and further characterized by said magnet-means having two spaced pole-pieces disposed so that north and south magnetic poles are formed at spaced places on the active cathode surface, in combination with means for preventing a formation of a cathode-spot on the main anode during the non-conducting periods of the device.

19. The invention as defined in claim 16, characterized by said ring-shaped starting-anode portion lying in a plane which is substantially normal to the active cathode surface, and further

10

20

12

characterized by said magnet-means having two spaced pole-pieces disposed so that north and south magnetic poles are formed at spaced places on the active cathode surface, in combination with an anode-shield for at times preventing a formation of a cathode-spot on the main anode during the non-conducting periods of the device.

20. The invention as defined in claim 16, characterized by said ring-shaped starting-anode portion lying in a plane which is substantially normal to the active cathode surface, and further characterized by said magnet-means being an electromagnet disposed outside of the evacuated container and having two spaced pole-pieces disposed so that north and south magnetic poles are formed at spaced places on the active cathode surface.
